(57) **CLAIM**

The ornamental design for a protective mobile telephone case, as shown and described.

DESCRIPTION

FIG. 1 is a frontal perspective view of a protective mobile telephone case, with a panel closed relative to a back side of the protective mobile telephone case, an inner surface of the panel positioned against the back side of the protective mobile telephone case, and the inner surface of the panel concealed between the panel and the back side of the protective mobile telephone case;

FIG. 2 is a rear perspective view of the protective mobile telephone case shown in FIG. 1;

FIG. 3 is a front view of the protective mobile telephone case shown in FIG. 1;

FIG. 4 is a rear view of the protective mobile telephone case shown in FIG. 1;

FIG. 5 is a top view of the protective mobile telephone case shown in FIG. 1;

FIG. 6 is a bottom view of the protective mobile telephone case shown in FIG. 1;

FIG. 7 is a left side view of the protective mobile telephone case shown in FIG. 1;

FIG. 8 is a right side view of the protective mobile telephone case shown in FIG. 1;

FIG. 9 shows the protective mobile telephone case shown in FIG. 1, with the panel open relative to the back side of the case; FIG. 9 provides a plan view of the inner surface of the panel; and,

FIG. 10 is a rear perspective view of the protective mobile telephone case shown in FIG. 1, with the panel open relative to the back side of the case, exposing the inner surface of the panel.
